(57) **CLAIM**

The ornamental design for a magnetic searching system for electrical boxes, as shown and described.

DESCRIPTION

FIG. 1 is a top view of a magnetic searching system for electrical boxes showing my new design;

FIG. 2 is a bottom view;

FIG. 3 is a side view;

FIG. 4 is another side view;

FIG. 5 is a top and side perspective view; and,

FIG. 6 is a bottom and side perspective view.

The lettering on the ornamental design as seen in FIGS. 1, 2, 5 and 6 forms no part of the inventive design.

1 Claim, 6 Drawing Sheets

FIG. 1

FIG. 2

FIG. 3

FIG. 4

FIG. 5

FIG. 6
